PHOTOALIDADE

Ronald M. Wilson, Bethesda, Md.

Application October 30, 1939, Serial No. 301,961

10 Claims. (Cl. 33—1)

(Granted under the act of March 3, 1883, as
amended April 30, 1928; 370 O. G. 757)

The invention described herein may be manufactured and used by or for the Government of the United States for governmental purposes without the payment to me of any royalty thereon, in accordance with the provisions of the act of April 30, 1928 (ch. 460, 45, Stat. L. 467).

This invention relates to means for and methods of making maps or plans from oblique photographs taken from airplanes, airships, elevated camera stations or ground stations, and more particularly to an improved photoalidade and the method of using the same. The use of the photoalidade in photogrammetric surveying is comparable to the use of the well known plane table and telescopic alidade in ordinary ground surveying.

Instruments and methods already known in the art that are somewhat similar to the instant invention in use and principle are the Bagley photoalidade, described in United States Geological Survey bulletin 657, 88 pp. 1917; the "High Oblique Plotter" used in Canada (see article by Burns and Field, entitled "A Plotter for High Oblique Air Photographs"), published in the Canadian Journal of Research, section A, vol. 13, pp. 22-35, 1935; and the bulletin entitled Canada Topographical Survey, a graphical method of plotting oblique aerial photographs, 21, pp. Ottawa, 1928; paper presented by R. D. Davidson, entitled A Plotter for Oblique Photographs, in the Proceedings of 29th Annual Meeting of the Canadian Institute of Surveying, held at Ottawa February 5th and 6th, 1936, published in the Canadian Surveyor, special edition, 1936, pp. 20-27; and the instrument designed by Mr. O. M. Miller of the American Geographical Society, described in the article entitled Notes on the construction of the Cape Chidley sheet, appendix 1 to Forbes, Alexander, A Flight to Cape Chidley, 1935, published in the Geographical Review, vol. 26, No. 1, pp. 53-56, 1936.

These instruments have been used for some time to produce maps from oblique photographs without resorting to stereoscopic vision by employing the ordinary surveyor's method of intersection for determining the desired location of points.

The Bagley photoalidade uses only panoramic photographs taken from ground stations, with the camera carefully leveled on a tripod. It is the predecessor of the photoalidade forming the subject-matter of this specification, and the general principles of surveying employed in the old and new instruments are the same, but the adaptation is entirely different.

The high oblique plotter and Mr. Miller's instrument apply the same general surveying principle, but in design they are more closely related to the largely mechanical plotting machines than to the simpler instruments used by surveyors in the field.

In the present invention it is proposed to make the practice of photogrammetric surveying similar to that of the plane table and alidade already so familiar to topographic engineers, and to make the apparatus used therein as simple and fool-proof as possible.

The new instrument with which this specification is concerned has been described in published articles as follows: "A New Photoalidade" by R. M. Wilson, published on November 6, 1937 in "The Military Engineer," vol. XXIX, No. 168, Nov.-Dec. 1937; "Oblique Photographs and the Photoalidade" by R. M. Wilson published in "Photogrammetric Engineering," issue of April-May-June 1938. The instrument was exhibited at the annual meetings of the American Society of Photogrammetry and the Geological Society of America, held in Washington in 1938.

The photoalidade described in this specification is not like the stereoscopic plotting machines now in common use in the art of photogrammetry such as the aerocartograph, the stereoplanoigraph, the multiplex projector, and others, because these machines employ the principles of stereoscopic vision, and ordinarily are used with vertical axis photographs. Also, these machines are very complicated and are so expensive as to be beyond the reach of ordinary surveyors; they are described in texts on photogrammetry and in articles published in technical journals.

An object of the present invention is to provide a device enabling one to make maps from oblique photographs using the methods of intersection for position and trigonometric leveling for altitude that are ordinarily used with a plane table and telescopic alidade in mapping from ground stations.

Another object of the invention is to provide an instrument by means of which the same observations may be made from a photograph that a surveyor might make if he could set up his plane table at the point where the picture was taken.

Another object of the invention is to extend graphic control with oblique photographs as an aid in strengthening the compilation of vertical photographs into mosaics or planimetric maps.

A still further object of the invention is to provide a means for making slotted templates

from oblique photographs for use in adjustments of photographs by the slotted template method.

A further object of the invention is to reduce information on photographs taken as records into the form of true scale plans or diagrams. For example, photographs of a street traffic accident, taken from two or more different points of view may be used to prepare a plan of the locality with vehicles and other objects shown accurately to scale in their relative positions.

Other objects and advantages of the invention will be apparent to one skilled in the art to which the specification relates in the light of the accompanying drawings in which—

Fig. 1 is a perspective view of the new photolidade.

Fig. 2 shows in section the details of the optical collimator.

Fig. 3 is a plan view of the instrument from above, while

Fig. 4 is a side elevation.

The instrument includes a supporting frame, carrying a holder for a photograph, a sighting telescope mounted so as to move as a unit with a vertical spindle, and a ruler attached to the spindle which guides the drawing of lines of direction on a map corresponding to directions sighted to features on the photograph, together with means whereby vertical angles may be observed for calculating difference in altitude, and an optical collimator for placing a given point on the map exactly in the vertical axis of the spindle, extended.

In the drawings reference numeral 1 denotes a triangular frame having three widely spaced legs 2 which hold the frame above a work table at a height convenient to the operator, leaving the table top nearly free for laying out the maps or drawings being worked upon.

Supported by the triangular frame 1 is a sighting telescope 3, mounted comparable to the telescope in a surveyor's transit, so as to point up or down, tilting upon the horizontal supporting axis 4 at right angles to its line of collimation shown by the line 5. The tilting motion of the telescope 3 is controlled by a clamp 6 and a slow motion screw 7 similar to the mechanism of the conventional surveyor's transit. A vertical angle arc and vernier scale 8 is provided so that angles of elevation or depression of the telescope can be measured. The vernier is adjusted to read zero when the line of collimation of the telescope is at right angles to the vertical axis 9 of the instrument. The line of collimation 5 and the two axes 4 and 9 pass through a common point 10 to be referred to hereafter as the center of the instrument.

The telescope mounting 11 is carried on the upper end of a spindle 12 which turns in a bearing 13 fastened to the main frame of the instrument. The telescope mounting can be revolved with respect to the spindle, this motion being controlled by a clamp 14 and slow motion screw 15. Thus the telescope may be pointed in different directions by turning it about the vertical axis 9 in order to point to any part of the photograph 16 from which measurements are to be taken.

The photograph is clipped to the holding plate 17. This plate is so mounted on parallel bars 18 that it can be moved toward or away from the center 10, but the plane of its surface is held at all times at right angles to the direction of the bars. The bars are graduated on their upper surface so that the plate 17 may be set at any 70

desired distance from the center 10. The bars are pivoted on pivots 19 and 20 and form part of the framework upon which the photograph 16 is carried. Therefore the entire framework may 5 be elevated or depressed by rotation about the axis 21 which, by construction, passes through the center 10 and is at right angles to the vertical axis 9. The position of tilt of the bars 18 may be maintained by the clamp 22 and slow 10 motion screw 23. Thus a point 24 may be marked on the plate 17 from which a line erected perpendicular to the plate will also pass through the center 10. The photograph 16 is fastened to the plate 17 with its optical center superimposed exactly on the marked point 24 on plate 17 so that the optical or principal axis of the photograph, thus constrained to coincide with the perpendicular just mentioned, will also pass through the center 10.

20 Also, the photograph may be revolved about its center on the plate to further adjust it in proper position. By the adjustments described the photograph can be placed relative to the center 10 so that as seen from that point as perspective center it will represent accurately the actual view as seen from the camera station.

To the lower end of the spindle 12 is hingedly fastened the arm 25 which is attached to the spindle by the hinge 21. The ruler 26 used to draw lines upon the map or work sheet is hingedly fastened to the end of the arm 25 opposite the spindle 12 by means of the hinge 28. The axes of the hinges 27 and 28 are parallel. By this arrangement the ruler 26 lies flat and 30 adjusts itself to the minor irregularities of the map surface, and it may be lifted easily to be out of the way when inspecting or moving the map, but still it is controlled so that its ruling edge always passes through the point where the vertical axis 9 intersects the map, indicating directions from that point corresponding to the directions in which the telescope is used.

40 Thus it is seen that with the clamp 14 tightened the telescope 3, spindle 12, arm 25, and ruler 26, all must revolve together through the same angles about the same vertical axis 9.

As it is necessary to place the map under the instrument with a given point on the map exactly under the center 10, an optical collimator 50 is built into the spindle 12, the line of sight from its eye piece 29 being turned downward by the prism 30 through the objective lens 31, so as to show where the vertical axis 9 intersects the plane of the map. The map can be shifted until the given point appears at the intersection of the cross hairs in the collimator.

The function of the photolidade is to utilize, for surveying purposes, the information contained in oblique photographs taken from airplanes or from ground stations. When the position, altitude, and orientation of the camera are determined for the instant of an exposure, the resulting photograph can be used in the photolidade: First, to draw lines of direction upon a map or plan from the plotted camera station through the locations of points identified on the photograph and, second, to read vertical angles as recorded by the photograph at the camera station from the horizon to points on the ground.

If the camera is not used at an established ground station where it can be carefully leveled, and where its position, elevation, and orientation can be determined directly, it is necessary to resort to the principles of resection to determine these elements for the camera station. The re-

section is always necessary when the photographs have been taken from an airplane. If three or more properly distributed control points, whose positions and elevations are known, can be identified in the photograph, the resection is usually possible.

In general, the angles formed between lines to these control points from one point of view are not duplicated from any other point of view. It follows, therefore, that the angles may be used to determine the position of the point of view with respect to the control points. In plane surveying this is called the "Three point problem"; the solution is more complicated when three dimensions are involved, although the principle is the same. There are established methods by which the position and altitude of the camera station can be determined by mathematical computations, beginning with measurements made on the photograph between the images of the control points. Such rigorous solutions are very laborious. But the photoalidade can be used to solve the problem graphically in a very short time, using the method described in the published article entitled "Oblique Photographs and the Photoalidade" (April, May, June 1938, Photogrammetric Engineering, pp. 65-74) which is incorporated herein by reference. The method is one of successive approximations, but leads quickly to a solution that is within the limits of error of the work done by the instrument.

When the position and orientation of the camera station have been determined by resection from the control points, and the corresponding settings of the instrument are effected, angular measurements taken with the telescope will be the same as if the surveyor's instrument were set up at the camera station, taking angular measurements from that point to the actual landscape. Thus, lines of direction may be observed to new points whose locations are sought. Such lines radiating from only one camera station, resulting from the use of a single photograph, do not immediately locate the new points; it is necessary to obtain similar radiating lines to the same points from another camera station. Then the positions of the points sought are found where corresponding lines from the two camera stations intersect. This is the well known principle of intersection that has been used in plane-table surveying for a great many years. The use of the photoalidade makes it possible to use this principle of intersection from camera stations in the air just as it has been used in the past from plane-table stations on the ground.

Vertical angles also may be measured to the new points whose positions have thus been determined, and by a simple calculation their elevations may be determined also. These points then may be used to guide the sketching of contours in reconnaissance mapping, or to use as control for compiling vertical photographs by other methods of photogrammetry.

The method may be used also with photographs taken with ordinary hand cameras, recording progress in engineering construction, to locate points of particular interest. Photographs taken immediately following a traffic accident may be used in the photoalidade to determine the position of vehicles, obstacles, or other objects that may be important in the case.

To describe the manipulation of the instrument, consider first the most simple case when a photograph has been taken from a ground station of known elevation, with the camera accu-

rately leveled. The horizontal axis of the photograph should then represent the true horizon. Now, referring to Fig. 1, slide the holder 17 forward or back on the graduated bars 18 of the frame, until its front face is at a distance from the center of the instrument 10 that is equal to the focal length of the camera. Prick a small hole in the photograph where the axis passes through its center. The photograph 16 is placed on the holder 17 with its pricked center on the center point of the holder. Since the camera was leveled, its optical axis was horizontal, therefore set the reading of the vernier 8 so that the line of collimation 5 will be perpendicular to the main axis 9 of the instrument. Then (see Fig. 4) by the clamp 22 and slow motion screw 23 raise the holder 17 and its frame 18 until the leveled line of collimation 5 will pass through the center of the photograph when the telescope is pointed in its direction. Next rotate the photograph about its center on the holder until its horizontal axis is in the plane at right angles to the axis 9 of the instrument so that looking through the telescope 3, the intersection of its cross wires (which represent the line of collimation) appear to follow along the horizontal axis of the photograph as the telescope is turned from side to side.

But generally the camera will not be leveled exactly; in fact it is usually desirable to tilt the axis of the camera down to include more of the landscape and waste less of the photograph on sky. Also, the camera may not be leveled transversely. Thus the line on the photograph that represents the true horizon generally does not coincide with the horizontal axis of the photograph, but instead it is most often near and only approximately parallel to the upper edge of the photograph. If the camera was used at a ground station of known position and elevation, and control points appear in the photograph, it is easy to compute the true vertical angles from the camera to those points. The photograph 16 is placed as before on the holder 17 with the distance from 10 to 24 equal to the focal length of the camera. Then the inclination of the holder arms 18 are adjusted by the clamp 22 and slow motion screw 23, and the photograph is rotated on its center, until the computed vertical angles read correctly on the arc and vernier 8 when the telescope is pointed to the corresponding images of the respective control points. The true horizon line may then be drawn by noting the line that the crosswires follow across the photograph when the vernier 8 is set at zero, and the telescope is swung from side to side.

If the camera is not leveled, and the position and elevation of the camera station is not known, which is usually the case when photographs are taken from an airplane, it is necessary to draw a tentative horizon line on the photograph by rough estimation. Setting the photograph in the instrument so that this tentative horizon line lies in the plane perpendicular to axis 9 at point 10. Then by test observations it is possible to determine how much the inclination of the holder 17 should be changed by adjusting the slow motion screw 23, and how much the photograph should be turned about its center to refer further measurements to the true horizon.

When the photograph has been adjusted into place by one of the methods just outlined, the operator is ready to take observations upon any features or details in which he may be interested that show in the photograph. The map or plan upon which he is working is laid on the

table under the instrument, with the ruling arm 26 resting upon it. The map is shifted about until the point on it representing the position of the camera station is directly in the line of the vertical axis 9 of the instrument. This is accomplished by sighting through the centering collimator shown in Fig. 2 with prismatic eyepiece 29, right angle prism 30 and objective lens 31 so arranged that its line of collimation is turned downward to coincide with the axis 9. With the clamp 14 loosened the operator lays the ruler 26 along a line on the map that corresponds to the direction of a sight to a control point on the photograph, and directs the telescope to that point. Clamp 14 is then tightened to preserve the directional relationship between the line of collimation 5 of the telescope and the ruling edge 26. Then with his left hand the operator holds the far end of the ruler 26 at 28 and swings it, and the telescope 3 that now turns with it, to view any desired part of the photograph. With his right hand the telescope may be tilted up or down as may be necessary, and when the pointing is effected, a corresponding line of direction may be drawn upon the map along the edge of ruler 26. The vertical angle to the sighted point is read from the arc and vernier 8 at the side of the telescope.

The legs 2 hold the instrument on its frame 1 at a convenient height above the table. The operator can, at any time, lift the ruler 26 from the map without disturbing the settings of the instrument, because the hinges 27 and 28 are so arranged as to control the direction of the ruler 26, yet allowing it to be lifted up out of the way. Thus the placing of maps or drawings under the instrument is a simple matter.

What is claimed is:

1. An instrument for use in the making of maps from oblique photographs, comprising a supporting frame adapted to be placed on a drawing table to over-lie and allow relatively free access to a mapping surface on said table, a spindle mounted on said supporting frame for rotation about an axis substantially normal to the plane of the mapping surface thus established, a sighting device for establishing a line of sight, said sighting device being pivotally mounted on said spindle with the line of sight thereof intersecting the axis of said spindle and with the pivotal axis passing through the point of intersection of the line of sight and the axis of said spindle normal to the plane established thereby, an arm having one end hingedly attached to said spindle, a ruler hingedly attached to the other end of said arm with the hinge axes at opposite ends of said arm parallel to each other and to the plane of said mapping surface, whereby the ruler may lie flat on said mapping surface yet permitting it to be raised therefrom, said ruler being so positioned that the line defined by one edge thereof intersects the axis of rotation of said spindle, a support carried by said frame for supporting a photograph in viewable relation to said sighting device, means for adjusting the distance of the photograph support from said sighting device and means for adjusting the angle of tilt of said photograph support.

2. An instrument for use in the making of maps from oblique photographs, comprising a supporting frame adapted to be placed on a drawing table to over-lie and allow relatively free access to a mapping surface on said table, a spindle mounted on said supporting frame for rotation about an axis substantially normal to

the plane of the mapping surface thus established, a sighting device for establishing a line of sight, said sighting device being pivotally mounted on said spindle with the line of sight thereof intersecting the axis of said spindle and with the pivotal axis passing through the point of intersection of the line of sight and the axis of said spindle normal to the plane established thereby, an arm having one end hingedly attached to said spindle, a ruler hingedly attached to the other end of said arm with the hinge axes at opposite ends of said arm parallel to each other and to the plane of said mapping surface, whereby the ruler may lie flat on said mapping surface yet permitting it to be raised therefrom, said ruler being so positioned that the line defined by one edge thereof intersects the axis of rotation of said spindle, a platen for supporting a photograph carried by said frame on a member pivoted on an axis perpendicular to the axis of said spindle and intersecting the same and said line of sight, and means for adjusting said platen longitudinally of said member whereby the distance from the sighting device and the angle of tilt of the platen may be adjusted with respect thereto.

3. An instrument for use in the making of maps from photographs, comprising a supporting frame adapted to be placed on a mapping surface to over-lie the same and allow relatively free access thereto, a spindle mounted on said supporting frame for rotation about an axis substantially normal to the plane of the mapping surface, a sighting telescope for establishing a line of sight, said telescope being pivotally mounted on said spindle with the line of sight thereof intersecting the axis of said spindle and with the pivotal axis passing through the point of intersection of the line of sight and the axis of said spindle normal to the plane established thereby, an arm having one end hingedly attached to said spindle, a ruler hingedly attached to the other end of said arm with the hinge axes at opposite ends of said arm parallel to each other and to the plane of said mapping surface, whereby the ruler may lie flat on said mapping surface yet permitting it to be raised therefrom, said ruler being so positioned that the line defined by one edge thereof intersects the axis of rotation of said spindle, a picture supporting platen mounted on said frame, said platen being adjustably mounted with respect to said sighting telescope.

4. An instrument in accordance with claim 3 in which the telescope includes means for measuring vertical angles.

5. An instrument for use in the making of maps from oblique photographs, comprising a supporting frame adapted to be placed on a mapping surface to over-lie the same and allow relatively free access thereto, a short focus telescope mounted on said frame for universal movement in azimuth and elevation, a ruler adapted to lie in the plane of said mapping surface, said ruler being hingedly attached to the mounting of said telescope to be traversed therewith in azimuth by means of an intermediate linkage pivoted both to the telescope mounting and to said ruler about axes parallel to each other and parallel to said mapping surface, and a photograph supporting platen mounted on said frame for supporting a photograph in adjustable viewable relation to said telescope in a plane oblique to the plane of said mapping surface whereby the telescope may be pointed successively at points on a photograph carried by said platen with the ruler

moving azimuthally therewith on the mapping surface to indicate lines on said surface enclosing angles corresponding to the angular movement between sightings of the telescope.

6. An instrument in accordance with claim 5 including means for adjustably positioning the said telescope azimuthally with respect to said ruler.

7. The method of making maps on a mapping surface from a plurality of photographs of the same general locale made from different points, which comprises setting up first one of said photographs with respect to a reference point so that the angles subtended by said photograph at said reference point are similar to the angles subtended by the field photographed at the point said photograph was taken, and with the vertical angles of lines of observation from said reference point to various points on said photograph corresponding to the vertical angles of the lines of observation from the point said photograph was taken to the respective points on the field photographed, locating a point on said mapping surface representing in plan the point said photograph was made, sighting from said reference point to objects on said photograph marking the azimuthal directions of said objects from said reference point upon said mapping surface from the point thereon corresponding to the point said photograph was made, setting up a second one of said photographs with respect to a second reference point in the manner outlined in connection with the first photograph, locating a point on said mapping surface corresponding in plan to the point said second photograph was taken, sighting from said second reference point to objects on said second photograph, marking the directions of said objects from said second reference point upon said mapping surface from the point thereon corresponding to the point from which said second photograph was taken, and fixing on said mapping surface the position of the objects viewed in said photographs from the intersection of the lines marked on said mapping surface representing two lines of sight to the same objects.

8. The method of mapping which comprises taking a plurality of oblique photographs from a plurality of points of origin of an area to be mapped, setting up with respect to a point of sight one of said photographs with the optical center at the same distance from said point as the lens of the camera taking the picture was from the sensitized area on which the photograph was made and with the vertical angle of the principal axis from the point of sight to the optical center of the picture the same as the vertical angle of the principal axis of the camera was when the picture was taken, and with its plane oriented so that the angles subtended at the point of sight by objects on the photograph correspond

to the angles subtended by said objects in the area itself at the point of origin of the photograph, locating on a mapping area a reference point corresponding in plan to the point of sight of the set-up, marking relative to said point of sight on said mapping area angles in azimuth corresponding to the azimuth angles relative to said point of sight of points in said photograph, repeating the set-up and azimuthal angle marking with respect to a second photograph and a reference point located relative to said first reference point on the mapping area to correspond with the relative location of the corresponding points of origin, whereby the relative positions of points common to the two photographs are located on a mapping area by intersection of the azimuthal markings thereof.

9. The method of mapping which comprises taking with cameras of known focal lengths and at determinable vertical angles of principal axes from a plurality of points of origin, a plurality of photographs of an area to be mapped; setting up with respect to a point of sight, one of said photographs, with its optical center at the known focal distance and the determined vertical angle of principal axis from the point of sight, and with its plane oriented so that angles subtended at the point of sight between images on the photograph, correspond to the angles subtended between corresponding points in the area itself at the point of origin of the photograph; locating on a mapping area a reference point corresponding to the point of sight of the set-up, marking relative to said reference point on said mapping area angles in azimuth corresponding to the azimuthal angles relative to said point of sight of points on said photograph; repeating the set up and azimuthal angles making with respect to a second photograph and a reference point located relative to said first reference point on the mapping area to correspond with the relative location of the corresponding points of origin; whereby the relative positions of points common to the two photographs are located on the mapping area by intersection of the azimuthal markings thereof.

10. A photoalidade for use in the making of maps from a plurality of oblique photographs comprising a short focus telescope mounted for movement in azimuth and elevation, a ruler carried by said telescope when moved in a plane oblique to the horizontal plane in an azimuthal direction, said ruler being attached to the same vertical spindle that carries said telescope, and adjustable means for holding a photograph in the same position with respect to said telescope that the original field photographed occupied with respect to the camera taking it whereby when the telescope is moved in azimuth the ruler moves therewith permitting plane table surveying directly from a plurality of photographs.

RONALD M. WILSON.
